UNITED STATES PATENT OFFICE.

CLIFTON L. BUNDY AND ALBERT H. MANWARING, OF PHILADELPHIA,
PENNSYLVANIA, ASSIGNORS TO PHILADELPHIA ELECTRICAL &
MANUFACTURING CO., OF PHILADELPHIA, PENNSYLVANIA, A COR-
PORATION OF PENNSYLVANIA.

CUT-OUT.

No. 836,482.

Specification of Letters Patent.

Patented Nov. 20, 1906.

Application filed June 21, 1904. Serial No. 213,532.

To all whom it may concern:

Be it known that we, CLIFTON L. BUNDY and ALBERT H. MANWARING, citizens of the United States, and residents of Philadelphia, Pennsylvania, have invented certain Improvements in Cut-Outs, of which the following is a specification.

Our invention relates to cut-outs or switches for controlling electric current, and it consists of an improved device designed more particularly for use with arc-lamps, whereby the main line supplying current to the lamp-circuit can be closed and the lamp or lamps entirely disconnected, so that they can be handled without danger of shock.

Our improved switch, however, is available for use with any system for distributing electric current.

Our invention is fully shown in the accompanying drawings, in which—

Figure 1 is a front elevation of a structure embodying our invention with a portion of the same removed. Fig. 2 is a side elevation showing a portion of the structure in section on the line *a a*, Fig. 1. Fig. 3 is an enlarged plan view of the members forming the switch and the mounting for the same. Fig. 4 is a side elevation of the switch and its mounting. Fig. 5 is a plan view similar to Fig. 3, showing the switch in another position with the operating member or plug in place. Fig. 6 is a view similar to Fig. 5, showing the operating member or plug partially withdrawn; and Fig. 7 is a side elevation illustrating a detail of the operating member or plug.

As is well known, there is considerable danger connected with the handling of arc-lamps or arc-lamp circuits when current is passing through said lamps or circuits.

Our invention comprises means for disconnecting any lamp or any loop controlling a series of lamps when the current is on by detaching the wires leading to the lamp or loop controlling a series of lamps and closing the main line, thereby enabling the operator to handle the lamp or lamp-circuit without danger of receiving a shock.

In the drawings herewith, 1 represents the upper shell or casing of an ordinary arc-lamp, which is provided with binding-posts 2 for the current-supplying wires. This shell or casing is provided with a link 3, whereby it

may be suspended, and supported by a hook 4 is the structure carrying the switch or cut-out device from which the lamp is hung. 55 This structure comprises a casing 5 of any suitable form, to which is attached a series of insulating members 6, 7, 8, and 9. The members 6 and 7 form part of the supporting structure, while the members 8 and 9 are employed simply as supports for the leading-in wires 10 and 11, supplying the current, being connected thereto in any suitable manner. The insulating member 6 is carried by a ring and yoke-piece 12, suspended from the hook 65 4, and is provided with means whereby it may be locked to said hook, comprising the pivoted bar 13 and the set-screw 14. The insulating member 7 is also carried by a yoke and ring member 15, and said insulating 70 member carries a hook 16, from which the lamp structure 1 is suspended by means of the link 3.

Within the casing 5 is a block 17 of insulating material, carrying the switch structure, 75 which latter consists of a pair of segmental members 18 and 19, the former having a split end 20, formed by spring contact-plates 21, to receive the end 22 of the member 19, and both of these members are pivotally mounted on pins 23 and 24. Carried by said pins and fixed with relation to the block 17 are the binding-posts 25 and 26, to which are connected the leading-in wires 10 and 11 by means of suitable screws. The 80 switch members are free to turn on the pins 23 and 24, and to create a tension upon the same and prevent them turning too readily flat spring members 27 and 28 are provided, which spring members are interposed between said switch members and the fixed binding-posts and are held so as to move with the switch members by means of projecting portions 29, which enter openings 30 in said switch members. The block 17 is 85 disposed at an angle within the casing 5 and is secured therein by means of screws 31.

When the switch members are in the position shown in Fig. 3, the main line is short-circuited, the current passing from the main 100 to the leading-in wire 10, to the binding-post 25, thence to the switch members 18 and 19, thence to the binding-post 26, thence out through the leading-in wire 11, and the lamp

when the switch is in this position is entirely disconnected.

To connect the lamp, the following means are provided. The block 17, carrying the 5 segmental switch members, is disposed at an angle within the casing, as shown in Fig. 2, and the cover 32 of the casing, hinged at 33, is provided with an opening 34 in line with said block, which is cut away at the center, as 10 shown at 35. Arranged to enter this opening 34 is a plug 36, made of porcelain, wood, rubber, or other suitable insulating material. This opening is in line with the switch members 18 and 19, so that when the plug 36 is 15 entered and engages the far ends 20 and 22 of said switch members it will turn the latter upon their pivots and cause their opposite ends 20^a and 22^a to enter grooves or ways 37 in the sides of the plug, which grooves or 20 ways are provided with spring-metal clips 38, connected to wires 39 and 40, respectively, forming the lamp-terminals, which latter are attached to the binding-posts 2 of the lamp, being held by suitable means and 25 through which the current passes to the lamp. These spring-metal clips are held in place by suitable pins 41, the plug 36 being recessed, whereby said pins may be soldered or otherwise fastened in place, as indicated 30 at 42, and in the far end of the spaces between said spring-clips we mount rollers 43, as clearly shown in Figs. 5 and 6. The end of the plug is recessed at 44, and such recessed portion has a curved face on the same 35 as the switch members, so that when said plug is passed into the casing and brought into engagement with the rear ends of such switch members it will tend to separate the same and the continued movement of the 40 plug will open said switch and cause the ends 20^a and 22^a of said members to engage the spring-metal clips carried by said plug, and the lamp is thus thrown into circuit. When it is desired to disconnect the lamp, 45 the plug 36 will be removed, and in the act of removal the rollers 43 will engage the front ends 20^a and 22^a of the switch members and cause the same to open, and the rear ends 20 and 22 of said switch members will engage, 50 thereby closing the main line.

The opening for the plug is disposed at the under side of the casing, so as to prevent the access of water. The plug is provided with a projection 45, and a corresponding groove 55 46 is formed in the wall of the opening 34 in the cover of the casing, so that the insertion of said plug in its proper position will be insured.

As clearly indicated in Fig. 7, the spring-clips 38 are slightly curved toward each other, so that the engagement of the ends 20^a and 22^a of the switch members therewith can be readily effected and a good contact insured.

65 Although we have shown and described seg-

mental switch members, it will be understood that pivotally-mounted switch members of different shape may be employed.

Having thus described our invention, we claim and desire to secure by Letters Pat- 70 ent—

1. The combination, in a cut-out switch, of a pair of independent and pivotally-mounted switch members movable into and out of engagement with each other, supply-wires 75 connected to said members, and an independent member adapted to positively engage and move said switch members on their pivots both into an open as well as a closed circuit position; said latter member having 80 terminals connected to an electroreceptive device and arranged to be respectively engaged by said pair of switch members.

2. The combination, in a cut-out switch, of a pair of pivotally-mounted switch mem- 85 bers having supply-wires connected thereto, with a removable plug carrying terminals connected to an electroreceptive device, said plug being arranged to engage one end of each of said switch members to move their 90 opposite ends respectively into engagement with said terminals.

3. The combination, in a cut-out switch, of a pair of movable switch members, one of said members having a split end to receive 95 the other, pivot-pins on which said members are mounted, and springs for keeping said members under tension.

4. The combination, in a cut-out switch, of an insulated supporting-block, a pair of seg- 100 mental switch members, pivot-pins on which said members are mounted, binding-posts carried by said pins, supply-wires connected to said binding-posts, and springs interposed between said binding-posts and the switch 105 members.

5. The combination, in a cut-out switch, of a casing, a pair of switch members pivot-ally mounted therein and arranged so as to be capable of engagement with each other, 110 with a plug removably mounted in the casing and provided with terminals electrically connected to an electroreceptive device, said plug including means for engaging and separating said switch members when it is en- 115 tered in the casing and for positively moving said members into engagement with each other when it is removed from the casing.

6. The combination, in a cut-out switch, of a casing, a pair of movable switch mem- 120 bers carried in the casing and capable of engagement with each other, a removable plug carrying terminals, said plug being constructed to positively displace the switch members, and contact-pieces carried by the plug 125 so as to be engaged by said switch members to cut an electroreceptive device connected thereto into the main-line circuit, said plug provided with means placed to positively move said switch members into engagement 130

with each other when it is withdrawn from the casing.

7. The combination of the casing, independent segmental switch members carried therein, a main circuit to which said members are connected, said members being pivotally mounted and movable into and out of engagement with each other, a plug removable from the casing for positively engaging and moving said switch members upon their pivots in opposite directions, the casing having an opening for the plug provided with a straight grooved portion, and a projecting stud placed on said plug to register with the groove whereby said plug is positioned relatively to the switch members.

8. The combination of the pivotally-mounted segmental switch members, a plug for displacing the same, and spring-clips carried in the sides of said plug for the reception of the ends of the switch members.

9. The combination of the pivotally-mounted segmental switch members, a plug for displacing the same, and spring-clips carried in the sides of said plug for the reception of the ends of the switch members, said plug having a curved and recessed end to engage the switch members.

10. The combination of the pivotally-mounted switch members normally in engagement with each other, a plug having recessed sides and a grooved end to engage and separate said members and turn them on their pivots so that their front ends may enter the sides of said plug, spring-clips mounted in said sides, and means carried by said plug for engagement with said switch members upon the withdrawal of the plug to return said members to their normal position.

11. The combination of the pivotally-mounted segmental switch members normally in engagement with each other, a plug

having recessed sides and a grooved end to engage said members and cause them to separate and turn on their pivots so that their front ends may enter the sides of said plug, spring-clips mounted in said sides, and rollers for engagement with said switch members upon the withdrawal of the plug to return said members to their normal position.

45

50

12. The combination of pivotally-mounted segmental switch members, a main-line circuit connected thereto, a removable plug arranged to engage and positively turn said switch members in opposite directions on their pivots, and terminals carried by said plug and arranged to be engaged by the switch members to cut an electroreceptive device connected to them into the main-line circuit.

6c

13. The combination of a casing, independent switch members supported therein and movable into and out of engagement with each other, said members being pivoted and in frictional engagement with their mounting so as to remain in any position to which they are moved, a main-line circuit connected to said members, a plug removably mounted in the casing and constructed to engage and positively displace said switch members, both when it is entered and when it is removed from said casing, and terminals carried by said plug and arranged to engage the switch members to cut an electroreceptive device connected to them into the main-line circuit.
